MECHANICAL DEVICE

George S. Perry, Du Pont, Ga.

Application April 18, 1934, Serial No. 721,223

8 Claims. (Cl. 40—126)

This invention relates to a mechanical device, the primary object of the invention being to provide a device of this character which may be used in store windows or the like to attract the attention of people passing the window, to the end that articles placed in the window near the device, will be viewed.

A further object of the invention is to provide a device of this character which will be electric motor controlled, the electric motor of the device being hidden from view so that the appearance will be that of perpetual motion.

Another object of the invention is to provide a plurality of weights in the form of movable balls which will be released at predetermined intervals, and will assist the electric motor in rotating the several gears forming a part of the device.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a fragmental plan view of the device.

Figure 2 is an elevational or side view thereof.

Figs. 3 and 4 show the delivery end of the ball track.

Fig. 5 is an enlarged fragmental view of the shock absorber.

Fig. 6 is a detail view.

Referring to the drawings in detail, the device comprises supports indicated generally by the reference character 5, and as shown the frame on the supports comprises spaced side members 6 and 7 respectively between which the shafts on which the various gears are supported, are mounted. Side members 6 and 7 are spaced with parallel horizontal bars 8.

The reference character 9 designates a shaft on which the main or power wheel 10 of the device is mounted, the wheel being provided with a groove formed in its periphery, the groove being sufficiently wide to accommodate the balls 11 that assist the electric motor in supplying power to the device.

Pairs of pins indicated at 13 extend from the periphery of the wheel 10 and provide means for supporting the balls 11 and holding them in position on the wheel until the balls reach the

point where they are delivered to the track 14. This track 14 is formed with a curved extremity 15, and as shown the track is inclined downwardly, the opposite end of the track being curved inwardly as at 16.

Pivotedly mounted at one end of track 14 is a receiving member 17 which is formed with a forwardly extended portion 18 that provides a support for one end of the pivoted arm 19, which is normally resting thereon.

A spring indicated at 20 is secured to one end of pivoted member 17 and its other end fastened by means of adjusting screw 20^a to member 16 to normally urge the member 17 to a position so that it will extend slightly above the track 14, as clearly shown by Figure 4, the inner end of the member 17 presenting a shoulder to restrict movement of the ball that has passed member 17^a (see Figure 4) from the track 14.

The member 17 is pierced by chisel shaped bar 20^b. This bar is lying in path of travel of balls 11 in track 14, and normally rests flush with floor of track 14, but when member 17 is moved upwardly as shown by Figure 4 chisel shaped bar 17^b forms a scotch for all balls that may be in track 14.

The bar 17^b as clearly shown in Figure 3 also shown on Figure 2 moving upwardly urges ball in track 14 then resting against downward extension 22^b of member 22 to overcome its inertia 30 and move quickly to its place against shoulder 17^b of member 17, and when member 22 descends quickly behind said ball it is forced into depression 24 of arm 19, see Figures 3, and 4.

The throwing arm 19 is axle mounted on the 35 frame of the device. One end of the arm is dipper shaped with depression 24 for receiving a ball from track 14, and the other end of the arm 19 is provided with a flat upper surface to which is adjustably mounted member 49 to which 40 is attached one end of spring 40 the other end of coil spring 40 being attached to member 45. It is obvious that when roller 43 moves over the upper curved surface of member 44 it will force arm 45, to which it is firmly attached, downwardly causing coil spring 40 to pull member 49 downwardly causing arm 19 to which it is attached to move upwardly throwing the ball that is resting in depression 24 into ball runway or track 25 with sufficient force so that its momentum will carry it around curved end 25^b into track 25^a where it gravitates to its position between pins 13 on wheel 10.

Now when throwing arm 19 reaches the end of its upward stroke it comes in contact with coil 55

spring 61, which is solidly mounted on member 69 attached to the frame. This coil spring returns arm 19 quickly to normal position, that is resting on shock absorber 51 of extension 18 of member 17. This return movement of arm 19 to normal position forces member 17 downwardly through action of member 38 forcing extension arm 31 that is attached to extension 18 of member 17 downwardly. This downwardly movement of member 17 pulls part 22^b of member 22 downward quickly behind the ball then resting in the end of track 14 forcing the ball into depression 24 of throwing arm 19, track 14 being then flush with the inner end of member 17. Figure 3 shows track 14 flush with inner end of member 17. Figures 3 and 4 clearly show action of members when arm 19 is returned to normal position.

Mounted on the frame is a shaft 27 on which the cog wheel 28 is mounted, the shaft 27 being also supplied with a small cog wheel 29 that received motion from the shaft 9, through the cog wheel 30. Shaft 32 is also supported by the frame and receives motion from the shaft 9 through the medium of large cog wheel 28 mounted on the shaft 27 and substantially small cog wheel 35 mounted on shaft 32. Cog wheel 36 which is substantially large is also mounted on shaft 32 and transmits motion to the shaft 37 through medium small cog wheel 39 mounted on the shaft 31. Thus it will be seen that due to this construction, rotary movement of the power wheel 10, which is substantially slow is transmitted through the various cog wheels to the substantially heavy fly wheel 23, which is rotated rapidly causing the device to run smoothly.

Rotating arm 42 mounted on shaft 32 is provided with a roller 43 that engages member 44 with each revolution. This rotating arm 42 with each complete circle causes throwing arm 19 through medium of members 44, 45, 43 and 49 to deliver a ball into track 25 at the same time that member 26 forces a ball from wheel 10. This arrangement of parts will keep wheel 19 about one fourth full of balls at all times.

Wheels 30 and 29, and 28 and 35 are supplied with cogs in ratio rating, one cog on wheel 30 to equal one complete revolution of wheel 35.

The shock absorber is plainly shown in Figure 5. It tends to prevent the dipper end of throwing arm 19 from rebounding when it falls quickly after delivering a ball to track 25. Part 51 is an enlarged head against which the dipper strikes when it falls to normal position causing coil spring 53 to partly close up so quickly that slidably mounted weight 52 has barely overcome its inertia and started downwardly when it is met by a small head on lower end of rod 51^a. This weight takes the rebound from the dipper.

In the operation of the device, the movable ball weights 11 in conjunction with electric motor 12 tend to cause wheel 10 to rotate. This movement is transmitted to wheel 23 through the various cog wheels, causing the fly wheel 23 to rotate rapidly, its momentum tending to cause smooth running of machine. When the roller 43 moves over the top curved surface of part 44, the roller 43 engages the member 44 forcing the same downwardly and causing the arm 45 to which it is securely fastened to swing downwardly as shown in dotted lines in Figure 2 causing spring 40 which is attached to arm 45 and to member 49 to swing arm 19 upwardly, whereupon a ball which rests in the recess at the free end of arm 19, is thrown into the track 25 with sufficient force to cause ball to go around curve 25^b where it gravitates to wheel 10. The arm 19 contacting with

coil spring 61 now falls downwardly to its normal position where it contacts with member 18 through shock absorber 51.

When arm 19 moves upwardly it causes member 38 to describe nearly half circle upwardly releasing pressure on arm 31 allowing spring 20 to raise member 17 to a point regulated by adjusting screw 52. Screw 52 and its point of contact with member 17 is clearly shown in Figure 2. Now this upward movement of parts 19, 38, 17, 17^a and 22 results in a ball then in depression 24 of arm 19 being thrown into track 25, releases one of the balls retarded by member 22, blocks other balls in track 14 with member 17^a and also raises shoulder 17^b of member 17 to further retard the ball released by member 22.

Now when arm 19 is thrown against coil spring 61 it quickly returns to normal position, the dipper end resting on the enlarged head of part 51 in extension 18. This return movement causes member 38 to describe nearly half circle downwardly in its return to normal position forcing extension arm 31 downwardly causing member 22 to descend behind the ball being retarded by shoulder 17^b forcing said ball into depression 24 of arm 19 also placing downward pointed part 22^b of member 22 in the path of following balls in track 14 and also sinking part 17^a flush with the floor face of track 14 allowing following balls to come to rest against off face of part 22^b of member 22.

Figure 2 shows base 1 supported by two blocks one at each end. Block 2 is of solid material, block 3 is made to look just like block 2 but is hollowed out to form space for motor 12. The base 1 is also hollowed out to form a space for band wheel 76 on shaft 37 and band wheel 12^a on motor shaft 12^c, and grooved out for band 29 also indentation for member 4, said member 4 forming a bearing for one end of shaft 37. This is plainly shown on Figure 2 of the drawings.

I claim:

1. In a device of the class described, a frame, a power wheel mounted on the frame, means for rotating the power wheel, a track for delivering ball weights to the periphery of the wheel, a swinging arm on the frame for delivering the ball weights to the track, a track for delivering the ball weights to the swinging arm, and means for transmitting movement of the power wheel to the swinging arm to operate the swinging arm.

2. In a device of the class described, a frame, a power wheel mounted on the frame, means for rotating the power wheel, said power wheel having a groove formed in its periphery, pairs of pins extending from the periphery of the wheel, ball weights, a track for delivering the ball weights to the periphery of the power wheel, said ball weights resting between the pins, a swinging arm for delivering the ball weights to the track, means for operating the swinging arm at intervals, and means for restricting movement of the ball weights over the track.

3. In a device of the class described, a frame, a power wheel mounted on the frame, means for delivering ball weights to the periphery of the power wheel, said delivering means including a swinging arm, means for receiving ball weights from the wheel and delivering the ball weights to the swinging arm, and means for rotating the wheel.

4. In a device of the class described, a frame, a power wheel mounted on the frame, said power wheel having a groove in its periphery, means disposed adjacent to the groove for retaining weight

members deposited in the groove, means for delivering weight members to the groove, and means for receiving the weight members from the groove at intervals.

5. 5. In a device of the class described, a frame, a power wheel mounted on the frame, said power wheel having a groove formed in its periphery, a track mounted on the frame, one end of the track being disposed adjacent to the groove, ball
- 10 weights, means for depositing the ball weights in the track to be delivered to the groove, and a track for receiving the ball weights from the groove.
- 15 6. In a device of the class described, a frame, a power wheel mounted on the frame, said power wheel having a groove in its periphery, an electric motor to rotate the power wheel, a track for delivering ball weights to the periphery of the wheel, a swinging arm for delivering ball weights
- 20 to the track, means controlled by the action of the power wheel for swinging the arm upwardly at intervals, and means for receiving ball weights from the power wheel and delivering ball weights to the arm.
- 25 7. In a device of the class described, a frame, a power wheel mounted on the frame, an electric motor for rotating the power wheel, a track supported by the frame, ball weights, said ball weights adapted to move over the track and fall

onto the power wheel, a track for receiving the ball weights from the power wheel, a movable member at one end of the last mentioned track, a swinging arm for delivering ball weights to the first mentioned track, said swinging arm adapted to engage the movable member to release ball weights from the last mentioned track, and means controlled by the action of the power wheel for operating said swinging arm.

- 5 8. In a device of the class described, a frame, a power wheel mounted for rotary movement on the frame, a track inclined towards the periphery of the power wheel and adapted to deliver ball weights to the power wheel, a track for receiving ball weights from the power wheel, a movable member at one end of the last mentioned track, the movable member normally lying flush with the track to which it is connected to permit movement of ball weights in position on the track to depression in swinging arm, a swinging arm 15 adapted to rest on the movable member, means to prevent rebound of swinging arm when returned to normal position of rest on movable member, means for forcing a ball into depression in swinging arm, and means controlled by the action of the power wheel for swinging the arm and ball weight carried thereby, upwardly to deposit the ball weight on the first mentioned track.

GEORGE S. PERRY.
